UNITED STATES PATENT OFFICE.

WILLIAM F. ECKERT AND WILLIAM C. WHITCOMB, OF ROCHELLE, ILLINOIS.

MINE-LOCOMOTIVE.

1,082,740.

Specification of Letters Patent. Patented Dec. 30, 1913.

Application filed January 18, 1911. Serial No. 602,533.

To all whom it may concern:

Be it known that we, WILLIAM F. ECKERT and WILLIAM C. WHITCOMB, citizens of the United States, and residents of Rochelle, county of Ogle, and State of Illinois, have invented certain new and useful Improvements in Mine-Locomotives, of which the following is a specification, and which are illustrated in the accompanying drawings, 10 forming a part thereof.

The invention relates to explosive engines, and more particularly to those used upon locomotives.

The object of the invention is to provide improved means for cooling the cylinders of an explosive engine; and the invention contemplates a water-cooling and circulating system especially adapted for use upon locomotives intended to run in mines or 20 other places where clean water is not readily obtainable. The construction also provides that all of the exposed parts of a locomotive may be of stout and durable construction.

25. In the accompanying drawings, Figure 1 is a detail side elevation of a locomotive embodying the features of improvement provided by the invention; Fig. 2 is a detail plan view of the same; Fig. 3 is a longitudinal sectional view of a spray box used upon the locomotive, the plane of the section being indicated by the line 3—3 on Fig. 2; Fig. 4 is a detail sectional view taken on the line 4—4 of Fig. 3; Fig. 5 is a detail 35 sectional view showing a spray nozzle used upon the locomotive; Figs. 6 and 7 are similar to Figs. 3 and 4, respectively, but show a modified form of spray chamber, the plane of the section on which Fig. 7 is drawn being indicated by the line 7—7 on Fig. 6; and Fig. 8 is a transverse sectional view 40 of the locomotive taken on the line 8—8 of Fig. 2.

As shown in the drawings, the parts of the 45 locomotive are associated upon a wheeled frame, generally designated by the numeral 10. This frame preferably comprises a pair of longitudinal side sills 11 and 12, and an end sill or bumper 13.

50. The locomotive engine is generally designated by the numeral 14. It is shown as being mounted between the longitudinal sills 11 and 12 adjacent one end of the frame 10, and is of the so-called explosive type. The 55 engine preferably comprises a plurality of

power cylinders, as 15, 16, each having a chambered wall 17 for receiving a cooling fluid.

The power shaft of the engine 14 is shown at 18. This power shaft is most conveniently located upon the median line of the locomotive frame 10, and the power cylinders, as 15, 16, are preferably arranged in groups upon opposite sides of the power shaft. Water for cooling the power cylinders of the engine is delivered to the wall chamber 17 of each of the cylinders 15 and 16, through a pipe, as 19 and 20. Preferably both of the pipes 19, 20, branch, as at 21 (Figs. 1 and 2) from a common supply pipe 22. This supply pipe is shown as leading from a rotary circulating pump 23 located adjacent the front end of the locomotive frame. A bracket 24 is provided for supporting the circulating pump 23 in a 75 convenient position. As shown, the bracket 24 is formed upon the front end wall 25 of a housing or case 26, which incloses certain of the operative parts of the locomotive which pertain to the transmission of power 80 from the engine shaft 18 to the wheels of the frame 10 and include intermeshing bevel gears 70, 71, and speed-reducing gears 72, 73. The bevel gear 70 is mounted directly upon the power shaft 18. The gear 73 transmits 85 power to the wheels of the locomotive frame through sprocket chains 74, 75.

In the operation of the device, the circulating pump 23 draws water from a reservoir and delivers it to the wall chambers 17 of the power cylinders, as 15, 16, through the main supply pipe 22 and branch pipes 19, 20. The water is then delivered to spray boxes 29 and 30, where it is cooled, and from there it is returned to the reservoir. The reservoir is shown in the drawings at 27. It is conveniently located within the end sill or bumper 13 of the locomotive frame, this bumper, as shown, being formed as an integral chambered casting including the 106 reservoir. A pipe 28 leads upwardly from the foot of the reservoir 27 through its top to the intake side of the circulating pump 23.

The two spray boxes 29 and 30 are of 105 similar construction, but they are of complementary shape for disposition, respectively, upon the right and left hand sides of the locomotive frame. As shown in Figs. 1, 2, 3, 4 and 8 of the drawings, each of 110

the spray boxes comprises an oblong rectangular chambered casing located upon one of the side sills, as 11, 12, of the locomotive frame. The top of this casing is formed 5 double, as indicated at 77, 78 (Figs. 3 and 4), and provides a water passage 31 therein. Provision is preferably made for forcing air through the main body 76 of the chamber of the casing from end to end. A fan 10 32 is most desirably employed for forcing air through the spray boxes. This fan is shown as being located immediately in front of the engine 14. It may be of any well known form of construction, and preferably 15 includes a rotary blade 33, rigidly mounted upon the power shaft 18 and inclosed by a case 34, having discharge orifices, as 35, 36, adjacent its periphery. Each of the discharge orifices 35, 36, of the fan case is connected 20 to the main chamber 76 of one of the spray boxes 29, 30, by means of a tubular elbow, as 37, 38. Outlets for the escape of air delivered to the spray boxes by the fan 32 are provided at that end remote from 25 the connecting elbows 37, 38, in a screened laterally-directed aperture, as 39, 40, one of which is clearly shown in Fig. 1 of the drawings. Preferably suitable baffles, as 41, 42, are provided within the main chamber 30 76 of each of the spray boxes adjacent the air outlet opening, as 39, 40.

A plurality of spray nozzles, 43, one of which is shown in detail in Fig. 5 of the drawings, are provided for discharging 35 water from the passage 31 of each of the spray boxes into the main chamber 76 thereof, in the form of a spray. For returning this water to the reservoir 27, a connecting elbow pipe, as 44, 45, unites the forward 40 end of each spray box with the top of the reservoir. Each of the spray nozzles 43 is so constructed and secured in place that it may be separately removed for inspection or adjustment. As shown, the upper and 45 lower walls 77, 78, of each of the water passages 31 are provided with a plurality of registering apertures, as 46, 47 (Fig. 4). The apertures, as 46, formed in the upper wall 77 of the passages are preferably 50 threaded, while those, as 47, formed in the lower wall 78 preferably have smooth margins. The rear end portion 48 of each of the spray nozzles 43 is threaded for engagement with one of the threaded apertures 46, 55 while the forward end portion, as 49, of each spray nozzle has a close sliding fit in the corresponding aperture 47.

When in place, each of the spray nozzles 43 is surrounded intermediate its ends by 60 water contained in the corresponding water passage 31. In order that these nozzles may serve to discharge this water into the main chamber 76 of spray boxes to be engaged and cooled by air from the fan 32, each of the 65 spray nozzles has a discharge orifice 51

upon its inner or forward end, and laterally-opening induction ports 52, the outer or rear end of the nozzle being closed. For regulating the discharge from the spray nozzles, each is provided with an adjusting screw 53, which enters the spray nozzle from its inner end and has a flaring head 53^a. The flaring head 53^a of the adjusting screw 53 co-operates with the mouth of the orifice 51 to discharge water received in the water passage 31 into the main chamber 76 of the corresponding spray box in the form of a fan-like spray, the character of the spray and the quantity of water delivered being determined by adjustment of the screw. Access to the adjusting screw 53 for regulating it and for cleaning the spray nozzle may be readily had by removing the nozzle. For this purpose each of the nozzles is provided with a wrench-receiving socket 50 at its rear end. Preferably the water passage 31 of each of the spray boxes 29, 30, is connected at one end to the wall chamber 17 of one of the power cylinders, as 15, 16, of the engine 14, by a pipe, 90 as 54, 55.

The circulating pump 23 is conveniently driven from the power shaft 18 of the locomotive engine 14. As shown, a countershaft 56 is provided. This countershaft is 95 journaled in the walls of the casing 26 and projects through the end wall 25 thereof for connection with the pump. Intermeshing gears 57, 58 (Figs. 1 and 2), mounted, respectively, on the power shaft 18 and on the countershaft 56 adjacent the rear end of the latter, provide for the continuous operation of the pump whenever the engine 14 is in service.

Figs. 6 and 7 of the drawings illustrate a 100 form of spray box 59 which may be employed in lieu of those designated 29 and 30. The spray box 59 is provided with nipples 60 and 61, for connection, respectively, with one of the pipes, as 55, leading 105 from the wall chamber of one of the engine cylinders, as 16, and with one of the return connections, as 45, to the reservoir 27. This spray box is also provided with an air inlet port 62 for connection with one of the 110 elbows, as 37, leading from the fan 32. The nipple 60 communicates with a water passage 63 formed in the cover plate 64 of the spray box 59. The cover plate 64 is removable, and is normally held in place by bolts, 115 as 65, 66. The upper and lower walls, as 79, 80, of the cover plate 64 are provided with a plurality of registering apertures 67, 68, similar to the apertures 46, 47, provided in the upper and lower walls 77, 78, of the 120 water passages 31 of the spray boxes 29 and 30. These apertures may be fitted with removable spray nozzles 69, identical in construction with those shown at 43.

With the form of construction illustrated 125

in Figs. 6 and 7, any one of the spray nozzles 69 may be removed independently of the others for adjustment and cleaning, or access to the entire set of spray nozzles and to the interior of the main chamber 69 of the spray box, may be had by removing the cover plate 64.

We claim as our invention—

1. In a water cooling apparatus, in combination, a chambered casing having a double wall at its top, the two parts of the said double wall being separated by a water passage and having registering apertures, the aperture in the outer part of said wall being threaded, a spray nozzle having a lateral induction port intermediate its ends for communicating with the water passage of the said chambered casing, and having a head adapted to pass through the aperture in the outer part of said double wall and to enter and substantially close the aperture in the inner part of said wall, the rear end portion of the spray nozzle being threaded to engage with the threads of the aperture in the outer part of said double wall.

2. In a locomotive, in combination, a wheeled frame having longitudinal side sills and a chambered end sill, a pair of operatively connected power cylinders each having a chambered wall, operative connection between the power cylinders and a wheel of the frame, a spray chamber mounted on each of the side sills of the frame, connection between the foot of each of the said spray chambers and the chamber of the end sill, connection between the wall chamber of each of the power cylinders and the top of one of the spray chambers, and a circulating pump receiving from the chamber of the end sill and discharging into the wall chamber of each of the power cylinders.

3. In combination, a gas engine having a chambered wall, a storage chamber for water, a pump receiving from the foot of the said storage chamber and delivering to the chamber of the engine wall, a conduit leading from the chamber of the engine wall, a removable spraying plug set through opposite walls of the conduit and having a lateral induction port communicating with the chamber of the conduit, said spraying plug making a close fit with one of the walls of the conduit and discharging through the other wall thereof into the upper part of the said storage chamber, and means for driving a current of air through the spray discharged from the conduit by means of the plug.

4. In combination, a gas engine having a chambered wall, a storage chamber for water, a pump receiving from the foot of the storage chamber and delivering to the chamber of the engine wall, a conduit leading from the chamber of the engine wall and a removable spraying plug set through oppo-

site walls of the conduit and having a lateral induction port communicating with the chamber of the conduit, said spraying plug making a close fit with one of the walls of the conduit and discharging through the other wall thereof into the upper part of the said storage chamber.

5. In combination, a water conduit and a removable spraying plug set through opposite walls of the conduit and having a lateral induction port communicating with the chamber of the conduit, said spraying plug making a close fit with one of the walls of the conduit and discharging spray from the chamber of the conduit through the other wall thereof.

6. In a locomotive in combination, a wheeled frame having longitudinal side sills, power transmitting means including a water jacketed motor located between the sills of the frame and operatively connected with a wheel thereof, a chambered water cooling box mounted upon and extending along one of the said sills and forming therewith a wall for covering a part of the said power transmitting means, means for separating the water into a plurality of portions having an extended surface for cooling by direct exposure to the air within the chamber of the box and service and return connections between the water jacket of the motor and the water cooling box.

7. In a locomotive in combination, a wheeled frame having longitudinal side sills, power transmitting means including a water jacketed motor located between the sills of the frame and operatively connected with a wheel thereof, a water cooling box mounted upon and extending along one of the said sills and forming therewith a wall for covering a part of the said power transmitting means, means for separating the water within the cooling box into portions having extended surfaces, such water cooling box being provided with air induction and exhaust ports, and service and return connections between the water jacket of the motor and the water cooling box.

8. In a locomotive in combination, a wheeled frame, power transmitting means including a water jacketed motor carried by the frame and operatively connected with a wheel thereof, a chambered water cooling box mounted on the frame and constituting a protecting wall for covering a part of the said power transmitting means, means for separating the water into a plurality of portions having an extended surface for cooling by direct exposure to the air within the chamber of the box, and service and return connections between the water jacket of the motor and the water cooling box.

9. In a locomotive in combination, a wheeled frame, power transmitting means including a water jacketed motor carried by

the frame and operatively connected with a wheel thereof, a chambered water cooling box mounted on the frame and constituting a protecting wall for covering a part of the 5 said power transmitting means, means for cooling by evaporation the water within the chamber of the cooling box, and service and return connections between the water jacket of the motor and the water cooling box.

- 10 10. In a locomotive in combination, a wheeled frame having longitudinal side sills, power transmitting means including a water jacketed motor located between the sills of the frame and operatively connected with a 15 wheel thereof, a chambered water cooling box mounted upon and extending along each

of the side sills, the two sills and the water cooling boxes mounted thereon constituting a housing for covering a part of the said power transmitting means, each of the said 20 water cooling boxes being provided with air induction and exhaust ports and service and return connections between the water jacket of the motor and the water cooling boxes and means for separating the water within 25 such boxes into portions having extended surfaces.
